1

This invention relates to single or multi-head flat knitting machines, and has reference particularly to the mechanism incorporated in such machines for controlling yarn carrier stops when producing full fashioned hosiery and the like.

It is principally the intention to apply the invention to straight bar knitting machines.

A machine of the class to which this invention is confined includes two groups of yarn carriers located at respectively opposite ends of the machine, each yarn carrier being attached to a reciprocatory driver bar or rod. The yarn carriers of one end group are attached to alternate driver bars or rods of a set, whilst the yarn carriers of the opposite end group are attached to the intervening bars or rods. Moreover, to each carrier in such an end group there are provided, at the same end of the machine, a fixed end or "home" stop and also a longitudinally movable end stop the position of which latter is automatically variable as knitting proceeds. The yarn carriers included in each end group are associated with pieces adapted for contact with the fixed and movable end stops. The driver bars or rods, together with their yarn carriers and associated contact pieces, are brought into commission selectively. Ignoring for the moment means for the production of spliced or reinforced areas, there is, in a single head machine, only one yarn carrier attached to each driver bar or rod, this carrier being employed during the production of a single fashioned fabric blank. In a multi-head machine, on the other hand, two or more suitably spaced yarn carriers are attached to each driver bar or rod, depending on the number of fashioned blanks to be produced at a time. Now when any particular bar or rod is selected, the contact piece associated with the yarn carrier, or the appropriate yarn carrier, attached to the said bar or rod, first moves away from the fixed home stop and passes by the movable end stop at the same end of the machine. Then either the same contact piece (in the case of a single-head machine) or a contact piece associated with the other yarn carrier, or the remote yarn carrier of a set of three or more, on the same driver bar or rod (in the case of a multi-head machine), comes into contact with a longitudinally aligned movable end stop at the opposite end of the machine. Thereupon, the yarn carrier or carriers on the same bar or rod, reciprocates or reciprocate between the said two aligned movable end stops until the carrier or carriers is or are next taken out of commission—at which time it is necessary for the carrier bar

2

or rod to be returned to its original position with the first mentioned contact piece abutting the fixed home stop. Before such return can take place, however, the said contact piece must, of course, pass freely by the corresponding movable end stop, all as well known to those acquainted with knitting machines of the class concerned.

The principal object of the present invention is to provide, in a flat knitting machine of the class just described, a simple and compact yarn carrier stop control mechanism designed to facilitate the foregoing movements.

Another object is to provide improved mounting means for the yarn carriers combined with contact pieces of novel form and disposition, as will be hereinafter described.

According to this invention, a housing at each end of the machine for a group of movable end stops is adapted to be moved laterally, i. e. aside, in relation to the yarn carrier driver bars or rods for the purpose of enabling any contact piece associated with a yarn carrier attached to a selected bar or rod, when the latter is moved to take the said yarn carrier out of action, to pass by the appropriate movable end stop and return into contact with the corresponding fixed home stop.

Whenever a group of movable end stops has been moved bodily aside to enable a contact piece to pass freely by the relevant movable end stop, the group is then automatically restored to its original position in readiness for the proper functioning of the yarn carrier or carriers next selected and brought into operation.

In order that the invention may be more clearly understood and readily carried into practical effect, a specific constructional example of the improved yarn carrier stop control mechanism as applied to a straight bar full fashioned knitting machine will now be described with reference to the accompanying drawings, wherein,

Figures 1 and 1a are a front elevational view of so much of the said machine as is necessary to illustrate the application of the invention thereto,

Figures 2 and 2a are a plan view of the same, Figure 3 is a fragmentary perspective view showing more clearly the slidable housing at one end of the machine in which are mounted individual longitudinally movable carrier members for a group of movable end stops,

Figure 4 is a detail, part sectional view, illustrating the connections by which the movable end stop housings are pulled aside and the control means therefor,

Figure 5 is a side view as seen from the appropriate end of the machine, of the pawl and ratchet and associated mechanism for effecting the required step-by-step movements of the groups of movable end stops towards and away from each other.

Figure 6 is a perspective view illustrating an alternate manner of mounting a group of movable end stops in a laterally shiftable housing.

Figures 7-12 are a series of detail front elevational views depicting successive movements of a yarn carrier first when moving into commission away from a fixed home stop, and then when being taken out of action and returned to the said home stop, and

Figure 13 is a somewhat similar view to any one of Figures 7-12 showing, however, a particular arrangement of movable end stops and a contact piece suitable for use in a single head machine and adapted to reduce the width of the machine to a minimum, as will be hereinafter described.

Like parts are designated by similar reference characters throughout the drawings.

Referring to Figures 1 and 2, it will be seen that the full fashioned straight bar knitting machine includes a group of yarn carriers such as 1 at each end of the machine, each of these carriers being fitted with a tube 2 for guiding a yarn to the needles of the machine. Each yarn carrier 1, moreover, is mounted on a flat vertically disposed plate 3 which is attached by means of screws to a reciprocable driver bar 4. There is, therefore, a set of parallel driver bars 4 arranged one behind the other in the same horizontal plane. The yarn carriers 1 of one end group are attached to alternate driver bars 4, whilst the yarn carriers of the opposite end group are attached to the intervening driver bars. Thus, as, in the specific machine illustrated, there are seven driver bars 4 in the set, there will be a group of four yarn carriers 1 at the right-hand side, and a smaller group of three such carriers at the left-hand side of the machine. The pair of yarn carriers on the two driver bars nearest to the front of the machine (designated 11) are for supplying splicing or reinforcing threads, as will be hereinafter more fully described.

Each reciprocable yarn carrier driver bar 4 is mounted for movement longitudinally in a channelled bar housing 5 having attached thereto spaced guide rails 5a.

The reference numeral 6 in Figure 1 indicates a portion of the sinker head of the machine, and a few of the sinkers and dividers are indicated, in purely diagrammatic fashion, at 7.

In accordance with conventional practice, there is provided to each yarn carrier 1 of the groups at respectively opposite ends of the machine a fixed home stop 8 and also a longitudinally movable end stop 9. The plate 3 upon which each such carrier is mounted has formed upon the back thereof, adjacent to its upper edge a lug 10 constituting a contact piece adapted for contact with the relevant fixed and movable end stops 8 and 9 respectively.

As will be readily appreciated by those acquainted with the construction of knitting machines of the class concerned, all of the end stops 9 are outside stops for controlling the width of the fabric. In addition to such stops the machine is also furnished with two inside stops 11 for controlling the aforementioned pair of yarn carriers (11) supplying splicing or reinforcing threads. Each driver bar 4 to which a splicing yarn carrier 1 is attached, also has attached

thereto, at an appropriate distance away from the said carrier, an auxiliary plate 12 having formed on the back thereof a lug 13 constituting a contact piece for co-operation with the corresponding inside stop 11.

The well known arrangement of stops illustrated is suitable for either a single or a multi-head machine. In the case of a multi-head machine, however, each reciprocable driver bar 10 6 would have attached thereto two or more yarn carriers.

Referring to Figures 1, 2 and 3, it will be seen that there is provided for the group of six movable end stops 9, at each end of the machine, a corresponding number of individual carrier members 14 housed and longitudinally slideable within a housing 15 which, in accordance with the characteristic feature of this invention, is adapted to be moved laterally in relation to the yarn carrier driver bars 4, for the purpose of shifting the movable end stops aside en bloc and thereby enabling any contact piece 10 on the plate 3 of a yarn carrier attached to a driver bar moving to take the said carrier out of action, to pass freely by the appropriate movable end stop 9 and return into contact with the corresponding fixed home stop. As shown more clearly in Figure 3, each housing 15 is formed with longitudinally extending parallel grooves or channels 16 to receive the individual carrier members 14 which latter are in the form of toothed bars or racks (hereinafter for convenience referred to as "rack bars"). These rack bars are held in position within the housings by means of cover plates 17 which serve to close the initially open sides of the grooves or channels 16. The rack bars 14 are disposed above the rails 5 housing the corresponding yarn carrier driver bars 4. Each housing 15, moreover, extends across and is slideable laterally within a pair of fixed front and rear supporting brackets 18 and 19 respectively.

Extending between and mounted in suitable bearings in, each such pair of fixed brackets is a toothed roller or gear 20 the lower portion of which protrudes through an aperture in the corresponding cover plate 17 for engagement with all of the rack bars 14 of the relevant group. By reason of this construction, whenever the said toothed roller or gear 20 is turned, all of the rack bars meshing therewith will simultaneously be moved in the same direction and to the same extent: apart from this, whenever the corresponding housing 15 is moved laterally (aside), engagement between the rack bars 14 and the toothed roller or gear 20 will be maintained, thereby in turn maintaining the positions of the several movable end stops 9 of the group relatively to each other.

At its inner end, each of the rack bars 14 is slotted, as indicated at 21 in Figure 1, and to this slotted portion is affixed, by rivets 22, a bracket 23. Mounted for adjustment longitudinally upon each bracket 23 is a slide 24 adapted to be locked in position by means of screws 25. Pivotally mounted upon the slide 24 by a pivot pin 26 is one of the end stops 9. This stop can yield and swing forward freely, but is positively prevented from movement backwards by contact of a tail portion 9a thereon with the underside of the bracket 23, as shown in Figure 1. In this way, each end stop 9 is enabled to present a solid, unyieldable face 9b to the contact piece 10 on the plate 3 of the relevant yarn carrier when this is in commission.

By making the slides 24 longitudinally ad-

justable, the movable end stops 9 can be individually adjusted in relation to the rack bars 14 to enable the tubes 2 on the yarn carriers 1 to be correctly located between the sinkers at the knitting location.

Each slide 24 has accommodated therein a vertical plunger 27 which is controlled by a compression spring 28. The upper end of the stem of this plunger is screw-threaded to receive nuts 29 which, by contact with the top of the slide 24, serve to limit the downward movement of the plunger. Each of the plungers 27 is adapted for co-operation with a bevel formation 30 on the plate 3 of the appropriate yarn carrier for the purpose of checking the said carrier and preventing rebound thereof at the relevant end stop 9. That is to say, when the contact piece 10 of any selected yarn carrier, during operation of the latter, moves into engagement with an end stop 9, the associated spring plunger 27 will snap into position on the appropriate bevel formation 30, thereby firmly holding the contact piece in certain engagement with the said stop. In this way, a good selvedge line is imparted to the fabric. The plate 3 supporting a yarn carrier 1 for use in a multi-head machine would only require to have one bevel formation, either right or left hand. The same remark applies to the plate 3 of a splicing yarn carrier 11. For use in a single head machine, however, each yarn carrier plate 3 must be provided at respectively opposite sides of the contact piece 10 thereon with two bevel formations 30, one right-hand and the other left-hand. Plates of the last mentioned form are illustrated, by way of example, in each of Figures 6-13, whereas right and left-hand plates each having only one bevel formation 30 are shown in Figure 1. But for the sake of standardisation, it is proposed that the plates 3 shall all be made with two bevel formations 30 so that identical plates can be used in either a single or a multi-head machine.

As shown in Figures 2 and 3, the cover plate 17 of each movable end stop housing 15 has provided thereon an upstanding stud 31 to which is connected one end of a Bowden or like flexible cable 32 the opposite end of which is attached to a fulcrummed cam lever 33. The toe 34 of this lever is arranged to be acted upon by cams, such as 35 and 36, affixed to the control drum 37 of the machine. Each flexible cable 32 extends through and is movable longitudinally within a fixed tubular housing 38 one end of which is secured in a union 39 which is screwed into the back of the corresponding rear bracket 19. The opposite end of each tubular housing 38 is fixed in a bracket 40 located near to and above the cam lever 33. A compression spring 41, arranged to surround each cable 32, is interposed between the stud 31 and the corresponding union 39. The housings 15 are therefore adapted to be pulled aside by the cables 32, against the action of the springs 41, at the required times dictated by the common control means, and to be restored to their original positions by the said springs.

The rearmost rack bar 14 of each of the two groups of such bars has attached thereto a U-shaped element 42 (see Figure 2) which is engaged by a driving dog 43 mounted on a part which is slidably engaged with a guide rail 44 and is attached to a nut N in turn engaged with a screwed shaft 45. This shaft has right and left-hand threaded portions 45a and 45b—the portion 45a for engagement with the nut N carrying the dog 43 for driving the right-hand group of rack

bars 14, and the other portion 45b for engagement with the nut similarly carrying the dog for driving the left-hand group of rack bars. It is to be clearly understood, however, that each dog 43 of itself serves to move one rack bar only, corresponding movement being transmitted to the remaining rack bars of that particular group through the medium of the relevant toothed roller or gear 20.

To effect step-by-step movements of the groups of movable end stops 9 towards and away from each other to fashion the fabric being knitted, the screwed shaft 45 is adapted to be racked in one direction or the other by pawl and ratchet mechanism, through the medium of intermeshing gears of a ratio appropriate to the gauge of the machine, under the control of suitable timing or controlling means. Thus, as shown in Figure 5, the pawl and ratchet mechanism includes a single rack wheel 46 which is mounted to turn on a shaft 47 and is cut so as to have teeth 46a suitable for racking in either direction. To the rack wheel 46 is attached a gear wheel 48 arranged in mesh with a pinion 49 secured upon the screwed shaft 45. For cooperation with the rack wheel 46 there is provided a pair of opposed pivoted rack pawls 50 and 51 which are mounted on a reciprocable racking member 52 and are connected by a controlling tension spring 53. The racking member 52 is slidably engaged upon the shaft 47, and at its outer end is connected to a suitably fulcrummed bell-crank lever 54 adapted to be rocked from a cam-actuated lever (not shown), through the medium of a link 55. The said lever may conveniently be actuated by a cam on the main shaft of the machine. Pivotally mounted at 56 upon the racking member 52 is a selector bluff 57 the head 57a of which is located between the opposed pawls 50 and 51. The shank or stem 57b is slidably engaged in a socket 58 provided on a vertically movable slide 59 supported in a convenient part of a bracket 60. The lower portion of the vertical slide 59 is fitted with a pin 61 which works in a cam slot 62 formed in a horizontal slide 63 mounted between guideways in another part of the bracket 60. The outer end of the horizontal slide 63 is articulated to a further bell-crank lever 64 which is connected, by means of an intermediate link 65, with a lever 66 adapted to be actuated from the control drum of the machine. The construction and arrangement are therefore such that the selector bluff 57 is selected, by selective operation of the slides 59 and 63 to take up one of three positions, according to requirements. Thus, when the slide 63 is pulled into such a position that the pin 61 is located in the highest portion of the cam slot 62, the head 57a of the bluff 57 will be turned downwards to render the lower pawl 50 inoperative and to permit engagement of the upper pawl 51 with the rack wheel 46, as a consequence of which the said wheel will be racked anti-clockwise (as viewed in Figure 5). When on the other hand, the slide 63 is pushed into such a position that the pin 61 is located in the lowest portion of the cam slot, then the bluff head 57a will be swung upwards to take the pawl 51 out of action and permit engagement of the rack wheel 46 by the pawl 50, so enabling the said wheel to be racked clockwise. When the slide 63 is moved to an intermediate or neutral position so that the pin 61 becomes located in the central portion 62a of the cam slot 62, the bluff 57 will be horizontally disposed—with both

7
paws 40 and 51 riding idly over the teeth 46a of the rack wheel 46.

Referring now to the modification illustrated in Figure 6, the slides 24 upon which the movable end stops 9 of each group are pivoted are, instead of being mounted on individual longitudinally movable rack bars 14, adjustable in a housing constituted by a common cross slide 67 which is movable laterally (aside) in a bracket 68. In this case the bracket 68 itself is movable longitudinally step-by-step to impart the required longitudinal movements to the end stops 9 en bloc, for which purpose the said bracket is directly engaged with relevant threaded portion of the screwed shaft 45 and is supported upon and guided by a slide rail 69. As in the case of the housings 15 in the first described example, each of the cross slides 67 is adapted to be pulled aside at required times by a flexible cable 32 under the control of cams on the control drum 31, and to be restored to its original position by a tension spring 70. The union 39 into which the tubular housing 38 for the cable 32 is fitted, is screwed into a lug 71 on the bracket 68, and the appropriate end of the said cable is attached to a stud 72 on the cross slide 67. One end of the spring 70 is anchored to an upstanding projection 13 on the top of the bracket 68, whilst the opposite end of the spring is similarly anchored to a pin 74 on the cross slide 67.

As previously mentioned, in addition to the end stops 9, the machine is also furnished with two inside stops 11—one left-hand and the other right-hand. The inside stops 11 are not pivoted, as are the end stops 9, and are accordingly incapable of yielding movement in either direction. The solid contact faces of the inside stops 11 are indicated at 11a. As will be appreciated, the contact face of the right-hand inside stop is disposed in alignment with and adapted to co-operate with one of the movable end (outside) stops 9 of the group at the right-hand end of the machine, and the contact face of the left-hand inside stop being similarly disposed in alignment with and adapted to co-operate with one of the movable end stops in the group at the left-hand end of the machine. Each inside stop, moreover, is formed on a bracket 75 with which is associated a spring plunger 76 (similar to the hereinbefore described plungers 27) adapted for cooperation with a bevel formation 77 on the corresponding auxiliary stop plate 12 for the purpose of checking the movement and preventing rebound of this plate, and hence also of the splicing yarn carrier 11, whenever the contact piece 13 on the plate is moved into contact with the relevant inside stop 11. The bracket 75 on which the right-hand inside stop is formed is attached to one end of a rack bar 78, whilst the corresponding bracket provided with the left-hand inside stop is similarly attached to a rack bar 79, these two rack bars being disposed parallel to each other and mounted for step-by-step movement longitudinally within grooves milled in a housing 80 fitted with cover plates 81. The two rack bars 78 and 79 are so inter-connected by gear means as to be adapted to move longitudinally in opposite directions upon movement being imparted to one of the said bars only. Thus, as shown in Figures 1 and 2, the rack bar meshes with a pinion 82 on a spindle 83 which is mounted to rotate in suitable bearings in fixed brackets—one of which is indicated at 84 and assists in supporting the housing 80. Another fixed bracket, omitted from the drawings for

the sake of clarity, would also be provided at the front of the housing 80. The end of the spindle 83 remote from the pinion 82 projects rearwardly through the bracket 84 and has fitted thereon a pair of ratchet wheels 85 and 86 which are formed with respectively oppositely cut teeth and are adapted to co-operate with suitably actuated oppositely arranged pawls 87 and 88 whereby the spindle 83 and hence also the pinion 82 can be rotated stepwise in either direction according to requirements. The rack bar 79 supporting the left-hand inside stop is engaged by a pinion 90 on a further spindle 91 mounted for rotation in the aforementioned bracket, the two spindles 83 and 91 being directly geared together by a pair of intermeshing pinions 92 and 93 (Figure 2a) so that whenever the pinion 82 is rotated, rotation to the same extent but in the opposite direction will be imparted to the pinion 90. In this way, the two inside stops 11 are simultaneously movable step-by-step in opposite directions, in accordance with the movements imparted to the ratchet wheels 85 and 86, to determine the shape of the spliced areas of the fabric.

To enable a splicing yarn carrier 11 to be used, alternatively, in the same way as one of the ordinary yarn carriers for feeding yarn to a complete series of needles instead of merely to a few needles for splicing, provision may advantageously be made for temporarily taking the inside stops 11 out of action by moving them aside out of their normal line to permit the splicing yarn carriers to pass by them and make longer strokes. To this end, the housing 80 may be made slideable laterally in a direction at right angles to the driver bars 4 and the channelled bar housings 5, and be operated and controlled in a similar manner to the housings 15. Thus, the housing 80 is adapted to be drawn aside at predetermined times by a flexible cable 94 which is attached at one end to a fulcrummed cam lever 95 (Figure 2) operable by cams such as 96 on the control drum 31. The opposite end of the cable 94 is attached to a stud 97 on the housing 80. The cable 94 extends through and works in a tubular housing 98 the appropriate end of which is fitted in a union 99 screwed into the bracket 84. A spring may be provided for restoring the housing 80 to its original position after having been drawn aside.

The movements of a yarn carrier 11 complete with its plate 3 in relation to a fixed home stop 8 and a movable end stop 9 will now be briefly described with reference to Figures 7-12. In Figure 7, the yarn carrier 11 is inoperative, with the plate 3 in contact with the relevant home stop 8, which for illustration purposes is at the right-hand end of the machine. As will be seen, when the plate 3 is in this position, the contact piece 10 thereon is located immediately behind the appropriate movable end stop 9 in alignment therewith. Assume now that the carrier 11 is selected and brought into commission by movement of the reciprocatory driver bar 4 in the direction of the arrow in Figure 8. First, the plate 3 moves away from the home stop 8, and the left-hand side of the contact piece 10 acts on the end stop 9 turning the latter forwardly about its pivot 26 as shown in Figure 8. At the same time the left-hand bevel formation 30 on the plate 3 passes beneath the plunger 27 as a consequence of which the latter rides up onto the top edge of the plate and the spring 28 is compressed. After having tripped past the mov-

able end stop 9, at which time the plunger 27 is released, the yarn carrier 1 continues its movement towards the left-hand end of the machine and completes a stroke in that direction. Thereupon the carrier makes a reverse stroke until, as depicted in Figure 9, the right-hand side of the contact piece 10 comes into engagement with the face 9a of the end stop 9 to arrest the carrier. As previously explained, the stop 9 cannot yield in this direction by reason of the engagement of its tail portion 9a with the underside of the bracket 23. The operative carrier 1 now proceeds to move back and forth, feeding yarn to the needles, and being arrested at the end of each stroke in the direction towards the right-hand end of the machine by engagement of the right-hand side of the contact piece 10 with the face 9a of the end stop 9. Whenever this happens, the plunger 27 snaps into engagement with the left-hand bevel formation 30 on the plate 3 to check the position of the carrier and prevent rebound thereof at the end stop. During these movements, however, the rack bar 14 carrying the end stop 9 may be moved stepwise to vary the position of the said stop and so shape the fabric. When the last stroke of the yarn carrier 1 is nearly completed, immediately prior to the carrier being taken out of commission again (see Figure 10), the movable end stop 9, together with the remaining end stops of the group, is moved aside, thereby permitting the contact piece 10 to pass freely by the stop 9 (Figure 11) and return to the home stop 8 (Figure 12).

The plates 3, with their contact lugs or pieces 10 of narrow width the opposite sides of which constitute closely disposed contact faces, are eminently suitable for use in single head machines. As shown in Figure 13, a single contact piece 10 can thus co-operate with the appropriate movable end stops 9 operating from respectively opposite ends of the machine. This enables the width of such a machine to be kept to a minimum. In Figure 13, the two end stops 9 and the associated spring plungers 27 are shown practically the minimum distance apart, the opposite sides 10a and 10b of the contact piece 10 making contact with the right and left-hand stops respectively as the plate 3 reciprocates between the two. The left-hand bevel formation 30 on the plate 3 co-operates with the plunger 27 associated with the right-hand stop 9 to hold the contact piece 10 firmly in contact with the said stop at the termination of each stroke of the plate 3 to the right, whilst the right-hand bevel formation similarly co-operates with the plunger associated with left-hand stop to hold the contact piece against the same at the completion of each reverse stroke of the plate.

Naturally, it is the fact of forming the contact pieces on plates such as 3 which enables the yarn carrier driver bars 14 to be mounted in and enclosed by housings such as 5.

What we claim then is:

1. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, means for carrying the movable end stops, means for varying the positions of the said movable end stops

as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops and means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop.

2. In a flat knitting machine, in combination, a yarn carrier having associated therewith a contact piece, a reciprocatory driver bar to which said carrier is attached, a fixed home stop at one end of the machine, a movable end stop which is normally in alignment with the home stop, means for carrying the movable end stop, means for varying the position of the movable end stop as knitting proceeds, the said movable end stop being yieldable in one direction to enable the aforesaid contact piece to pass it when the yarn carrier is brought into action, but not in the other direction, a housing for the movable end stop carrier means, and means for moving the said housing laterally in relation to the driver bar to enable the contact piece when the yarn carrier is taken out of action, to pass freely by the end stop for return to the fixed home stop.

3. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, means for carrying the movable end stops, means for varying the positions of the said movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops, means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop, and means for automatically restoring a housing to

its original position after the corresponding group of movable end stops has been moved aside and so returning the said stops in readiness for further use.

4. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, means for carrying the movable end stops, means for varying the positions of the said movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops, means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop, means for automatically restoring a housing to its original position after the corresponding group of movable end stops has been moved aside and so returning the said stops in readiness for further use, and means for positively maintaining the varying positions of the movable end stops of each group during movement aside and restoration to its original position of the corresponding housing.

5. A combination according to claim 1, wherein each of the said housings is mounted on a slide arranged transversely with respect to the yarn carrier driver bars, and is adapted to be automatically moved aside at required times at the dictates of controlling means, through the medium of intermediate connections.

6. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, means for carrying the movable end stops, means for varying the positions of the said movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at

the end of each appropriate stroke of the then operating yarn carrier, a housing at each end of the machine for the carrier means of the corresponding group of movable end stops, cam means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop, and spring means for automatically restoring a housing to its original position after the corresponding group of movable end stops has been moved aside and so returning the said stops in readiness for further use.

7. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine means for carrying the movable end stops, means for varying the positions of the said movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops, a control drum, cam means on said drum, fulcrumed levers adapted to be actuated by said cam means, flexible cables between the said levers and the housings whereby the latter can be pulled aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop, and spring means for automatically restoring a housing to its original position after the corresponding group of movable end stops has been moved aside and so returning the said stops in readiness for further use.

8. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, carrier means upon which the movable end stops are pivotally mounted, selectively operable control means for moving the said carrier means longitudinally step-by-step in either direction to vary the positions of the movable end stops as knitting proceeds, each of the movable end stops being yieldable in one direction but not in the other so that whenever such a stop is contacted by a contact

piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops and means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop.

9. A combination according to claim 8, wherein the movable end stops are adjustable individually in relation to the said carrier means.

10. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, individual carrier members furnished with brackets upon which the movable end stops are pivotally mounted, selectively operable control means for moving the said individual carrier members en bloc longitudinally step-by-step in either direction to vary the positions of the movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the individual carrier members of the corresponding group of movable end stops, and means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop.

11. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, cross slides fitted with parts upon which the movable end stops of the respective groups are pivotally mounted, longitudinally movable brackets in which the said slides are accommodated, selectively operable control means for moving the said

brackets longitudinally step-by-step in either direction to vary the positions of the movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, means for moving the cross slides aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop.

12. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, individual toothed bars furnished with brackets upon which the movable end stops are pivotally mounted, selectively operable control means for moving the said individual toothed bars en bloc longitudinally step-by-step in either direction to vary the positions of the movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the individual toothed bars of the corresponding group of movable end stops, means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop, and in engagement with all of the toothed bars of each group, a correspondingly toothed roller for positively maintaining the varying positions of the movable end stops of the group during movement aside of the corresponding housing.

13. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine,

carrier means upon which the movable end stops are pivotally mounted, a screwed shaft having right and left hand threaded portions, connections between these portions of the said shaft and the movable end stop carrier means at respectively opposite ends of the machine, pawl and ratchet mechanism for racking round the screwed shaft in either direction, means for controlling the operation of the pawl and ratchet mechanism whereby the movable end stop carrier means are moved step-wise to vary the positions of the movable end stops at knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops and means for moving the housings aside relatively to the yarn carrier driver bars for the purpose of enabling any contact piece associated with the yarn carrier attached to a driver bar moving to take the said carrier out of action, to pass freely by the appropriate movable end stop and return into contact with the corresponding fixed home stop.

14. A combination according to claim 13, wherein the pawl and ratchet mechanism comprises a single rack wheel having teeth suitable for racking in either direction, and, for co-operation with the said wheel, a pair of opposed pawls controllable by selective operation of an associated bluff.

15. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, individual toothed bars furnished with brackets upon which the movable end stops are pivotally mounted, a toothed roller engaged with all of the toothed bars of each group, a screwed shaft having right and left hand threaded portions, a nut engaged with each such portion of the shaft, a driving dog which is mounted on each nut and engaged with one only of the toothed bars of the corresponding group, pawl and ratchet mechanism for racking round the screwed shaft in either direction, means for controlling the operation of the pawl and ratchet mechanism, the longitudinal step-wise movements imparted by a driving dog to the engaged toothed bar being transmitted to the remaining toothed bars of the group through the medium of the corresponding toothed roller whereby the toothed bars are movable en bloc to vary the positions of the movable end stops as knitting proceeds, each of the movable end stops being yieldable in one direction but not in the other so that whenever such a stop is contacted by a contact piece associated with a selected yarn carrier moving into operation the said stop will be tripped to enable the

contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the individual toothed bars of the corresponding group of movable end stops, and means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop.

16. In a flat knitting machine, in combination, yarn carriers, selectively operable reciprocatory driver bars to which said yarn carriers are attached, contact pieces associated with the yarn carriers, fixed home stops at each end of the machine with which the contact pieces associated with inoperative yarn carriers make contact, a group of longitudinally movable end stops normally in alignment with corresponding home stops at each end of the machine, means for carrying the movable end stops, means for varying the positions of the said movable end stops as knitting proceeds, each of the movable end stops being yieldable in one direction but not in the other so that whenever such a stop is contacted by a contact piece associated with a selected yarn carrier moving into operation the said stop will be tripped to enable the contact piece to pass by it but when the said yarn carrier is reciprocating during production of fashioned fabric the said stop, notwithstanding variations in the position thereof, will present a solid face to the contact piece at the end of each appropriate stroke of the then operating yarn carrier, a housing at each end of the machine for the carrier means of the corresponding group of movable end stops, means for moving the housings aside relatively to the yarn carrier driver bars for the purpose of enabling any contact piece associated with a yarn carrier attached to a driver bar moving to take the said carrier out of action, to pass freely by the appropriate movable end stop and return into contact with the corresponding fixed home stop.

17. A combination according to claim 16, wherein the toothed bars carrying the two inside stops are mounted in a housing which is movable aside in relation to the yarn carrier driver bars, for the purpose herein described.

EDWARD SAMUEL BARSBY.
ALFRED PERCY SAUNDERS.
